WORK HOLDER

Lowell L. Pricer, Hayward, Calif.

Application February 28, 1949, Serial No. 78,829

7 Claims. (Cl. 77—63)

1

This invention relates to a unitary work holder adapted to positively and clampedly secure work-pieces in place upon the bed of a drill press or other machine tool.

An object of the present invention is the provision of a work holder which may be variously mounted with respect to machine tools with which it may be used.

Another object of the invention is the provision of a clamp finger of a work holder such that the same operative setting thereof can be established and maintained during work on a succession of like pieces.

A further object is to provide a quickly actuatable clamping and releasing means for the clamp finger.

Yet another object of the invention is the provision of a work-holding device of the character described which provides for operative adjustments of the clamping finger relative to the tool to be applied to a workpiece to be held by it.

An added object of the invention is the provision of a clamping unit of the character described which can be readily swung out of the way during work-aligning operations, or when not in use, without the necessity of having to dismount it from the machine tool which mounts it.

The invention possesses other objects and features of advantage, some of which, with the foregoing, will be set forth or be apparent in the following description of a typical embodiment thereof, and in the accompanying drawings in which,

Figure 1 is a plan view of a present work holder, certain parts being broken away.

Figure 2 is a broken-away elevation of the work-holder.

Figure 3 is a longitudinal vertical section illustrating a typical working application of the work holder.

Figure 4 is a section taken on line 4—4 of Figure 3.

Figure 5 is a fragmentary section showing an alternate control means for a work-engaging finger of the holder.

Figure 6 is a section taken on the line 6—6 of Figure 3.

Figure 7 is a section taken on the line 7—7 of Figure 3.

Figure 8 is a perspective view of a drill press, illustrating the device mounted on an auxiliary bed-plate and in use.

Referring to the drawing in detail, my holder includes an elongated body member comprising an arm portion 10 of channel cross section with its open side facing downwardly from the upper

wall or web 11 of the arm. The arm 10 extends integrally and radially from a split clamping collar 12 having its lower end coplanar with the bottom edges of the sides 13 of the arm, and the collar 12 is split oppositely of the arm 10 and is formed with usual lugs 14 adapted to be drawn toward one another in a clamping action of the collar by means of a hand screw 15 extending through them. As particularly shown, the lugs 14 are engaged between the screw head 16 and a nut 17 which non-rotatively engages the lug 14 which is furthest from the screw head.

The inner faces of each of the side walls 13 of the arm 10 are formed at their outer end portions with relatively shallow parallel and mutually opposed slots 18, said slots extending inwardly from the extreme end of the arm radially thereof and cooperatively providing a track or guide for the reception of the ends of a fulcrum pin or roller 19 engaged intermediately through a clamping finger 20 which has pivotal and longitudinally adjustable relationships to the arm. The finger 20 extends forwardly beyond the arm 10 and terminates in a work-contacting end portion 21 which has its under face offset downwardly and which is longitudinally forked from its forward end to provide for a more positive clamping action by the finger and to also permit the straddling of a drill, tap, or other rotary tool by the applied finger as illustrated in Figures 3 and 8.

The inner end of the finger 20 is formed to provide spaced coaxial eyes 22 having their axis parallel to the pin 19 and rotatively mounting a cylindrical member 23 provided with an intermediate transverse threaded hole and in effect comprising a nut for use in a manner hereinafter brought out. A compression spring 24 is constantly operative between the arm web 11 and a point of the finger intermediate the nut 23 and the fulcrum pin 19 to urge the disposal of the working end 21 of the finger 20 in its limiting upper position, as indicated by solid lines in Figure 2. The spring 24 is retained in its operative position by having one end fixed in a seat socket 25 provided in the top of the lever 20 and having its other end slidably engaging a seat comprising a relatively short and shallow longitudinal slot 26 of uniform width provided in the under side of the upper wall 11 of the arm 10.

An elongated rectangular opening 27 is provided through and along the top wall 11 of the arm 10, and a covering plate member 28 is provided at the upper wall side for adjusted positioning longitudinally of the arm 10 while in bearing relation to the top of the arm. The plate

28 is provided intermediately thereof with a depending rectangular portion 29 which slidably fits between the sides of the opening 27 for restraining the plate to a solely longitudinal adjustment thereof. Rearwardly of the opening 27, the top of the arm wall 11 is provided with a series of transverse and parallel depressions 30 for receiving a lip 31 which depends from the under face of the plate 28 at its rear end, whereby to provide for definite adjusted positionings of the plate along the arm.

It will now be noted that the plate 28 is located above the cylindrical nut 23 carried by the finger 20, and rotatably mounts a finger-control member comprising a screw 32 passing slidably through a hole therein and having a lower threaded portion engaging the nut 23 which is rockable as a wristpin when the screw is reciprocated. The upwardly projecting portion of the screw 32 has a cam lever 33 pivoted thereto by means of a fulcrum pin 33', the present lever 33 is forked from one end to straddle the projecting end of the screw 32, and the pin 33' passes through both sides 33'' of the forked lever portion and is fixed therein whereby the pin is rotatable in a complementary transverse bore of the screw 32. A thrust washer 34 loosely receives the screw 32 and is arranged to have one face thereof bear against the top of the plate 28 while its opposite face is engaged by camming faces 35 or 36 provided by the fork sides 33'' of the lever 33, said faces being flat and making an included angle of substantially ninety degrees between them.

Referring particularly to Figures 2 and 3, it will be seen that the face 35 is closer to the axis of the screw 32 than is the face 36, whereby a swinging of the lever from its position shown in Figure 2 to its position shown in Figure 3 will result in a cam action between the cam face 36 and the thrust washer 34 to raise the screw 20 and the attached nut 23. This will cause a rocking of the finger 20 about the fulcrum pin 19 to move its working end 21 in a downward direction for exerting a positive clamping pressure against any workpiece which it may then contact. By adjustably rotating the screw 30 in an appropriate direction, the clamping and releasing positions of the cam faces of the lever 33 can be adjusted relative to the surface of the work with which the finger 20 is to make operative contact, this arrangement making any further screw adjustment unnecessary when like workpieces are to be similarly worked on successively. Since the cam faces intersect at a line which is further from the pin axis than the faces, the camming head of the lever 33 will tend to remain set in either its operative or inoperative position.

An alternate means for controlling the finger 20 is shown on the fragmentary section of Figure 5, wherein a hand-screw 37 replaces the screw 32 and the cam lever 33 to facilitate applications of the finger to differing workpieces, it being understood that the essential value of the cam lever arrangement lies in the provision for successive like settings of the finger in a particularly speedy and accurate manner.

It will now be noted that the described work-holding unit has been particularly arranged for use in fixing a workpiece against a bed or table of a machine by which a rotary tool is advanced against a workpiece disposed on the bed or table. As illustrating a typical use of the present work-holder, Figures 3 and 8 show the holder as operatively associated with a drill-press A having a

base B, and a post or standard P fixedly related to the base B and adjustably supporting a head H which provides a rotary tool T for application against a workpiece W supported from the bed-plate B' of the base B. In the present instance, the workpiece W comprises a tubular sleeve or bushing which is directly supported in a V-block V for the working application of the tool T (drill) radially against it; for descriptive convenience, an actual workpiece and any associated base member, as the V-block V, may be collectively considered a workpiece.

In the present drill-press structure, the post P thereof is cylindrical and is assumed to be of the appropriate size for its clamped engagement in the clamp collar 12 of the present unit whereby the unit may be directly mounted on the post in adjusted position therealong to dispose the finger 20 of the holder in position to span the drill T as the same is applied to a workpiece mounted directly on the base bed-plate B'. When the present holder is mounted on a post P, the clamp screw 15 may be loosened to provide for swinging adjustments thereof over the bed-plate or displacement out of the way of the holder about the post.

Since, however, the head-supporting posts of various machine tools with which the present holder might be used may not be alike, means are preferably provided for mounting a present holder unit in operative position with respect to a machine tool independently of the post structure of a machine with which it is to be used. Accordingly, and as is illustrated in Figure 8, a mounting post 38 is provided on an auxiliary bed-plate 39 which is in turn arranged to be mounted on or screwed to a machine bed-plate such as the bed-plate B' of the present machine A. The plate 39 may solely rest upon the top of the bed-plate B', or be positively secured to the bed-plate by C-clamps or by means of bolts engaging the conventional T-slot of such bed-plates. Figures 3 and 8 disclose the tubular workpiece W as engaged by a drill T while resting in the trough of the V-block V which stands on the bed-plate 39 supported on the bed-plate B'. It will be understood that the combination of a present holder arm unit and the post 38 and the base plate 39 comprises a unitary positioning and holding clamp for the workpiece, and that the longitudinal adjustment of the rockable finger 20 along the arm 10 which is permitted when the finger 20 is in operation, provides for the most efficient application of the finger to the workpiece for clampedly holding it fixed with respect to the plate 39 while providing for the application of a tool to the workpiece directly through or beside the forked end of the finger.

From the foregoing description taken in connection with the accompanying drawings, the advantages of the present work holder will be readily understood by those skilled in the art to which the invention appertains. While I have described the principle of operation, together with arrangements which I now consider to be preferred embodiments thereof, I desire to have it understood that the showings are primarily illustrative, and that such changes and developments may be made, when desired, as fall within the scope of the following claims.

I claim:

1. In a device for clampedly holding a workpiece against a bed-plate, an arm fixedly related to the bed-plate in spaced opposed relation thereto, a clamping finger directly and inter-

mediately hinged to the arm and having a work-engaging forward end swingable toward and from the bed-plate and having its rearward end disposed beneath the arm, a wristpin journalled in the rearward end of the finger in fixed parallel relation to the axis of hinging of the finger and providing a transverse threaded bore, a control member threadedly engaged in the threaded bore of the wristpin and operative in tension between the top of the arm and the wristpin to clampedly engage the forward end of the finger with a work-piece disposed between it and the bed-plate, and means to reciprocate said control member in working and return strokes thereof.

2. In a device for clampedly holding a work-piece against a bed-plate, a clamping finger providing a work-engaging end and intermediately journalling a fulcrum pin having its ends extending laterally from the finger and fixedly related to the finger, and arm fixedly related to the bed-plate in spaced opposed relation thereto and providing a longitudinal rollway beneath its top and fittedly receiving the ends of the fulcrum pin of the finger for a longitudinally adjusted disposal of the finger therealong while the inner finger end is disposed beneath the top of the arm, and a control member operative in tension between the top of the arm and the underlying rear end of the finger to clampedly engage the work-engaging end of the finger with a work-piece disposed between it and the bed-plate.

3. A structure in accordance with claim 2 wherein the finger is disposed in a channel of the arm having its open side toward the bed-plate and having its sides providing the rollway for its fulcrum pin.

4. In a device for clampedly holding a work-piece against a bed-plate, a clamping finger providing a forward work-engaging end and intermediately mounting a fulcrum pin having its opposite ends extending laterally from the finger in fixed relation thereto, an arm fixedly related to the bed-plate in spaced opposed relation thereto and providing a longitudinal guideway beneath its top and fittedly receiving the ends of the fulcrum pin of the finger for a longitudinally adjusted disposal of the finger longitudinally along the arm and from beneath its top, a bearing plate engaging the top of the arm and adjustable along the arm as the finger, said arm being provided with a longitudinally extending opening, a control member operative in tension between the bearing plate and the rear end of the finger and extending through said top opening of the arm to clampedly engage the work-engaging end of the finger with a work-piece disposed between it and the bed-plate, and a spring means constantly and yieldingly operative between the rearward flange portion and the arm top to resist an operative action of the control means.

5. In a device for clampedly holding a work-piece against a bed-plate, a clamping finger providing a forward work-engaging end and intermediately mounting a fulcrum pin fixedly related to it and having its opposite ends extending laterally from the finger, an arm fixedly related to the bed-plate in spaced opposed relation

thereto and providing a longitudinal guideway fittedly receiving the ends of the fulcrum pin of the finger for a longitudinally adjusted projection of the finger from beneath its top, a bearing plate engaging the top of the arm and adjustable along the arm as the finger, said arm top being provided with a longitudinal slot therethrough, a wristpin journalled in the other finger end, a control member threadedly engaging the wristpin transversely of its rotative axis and extending through said slot and operative in tension between the wristpin and the bearing plate, and means independently cooperative between the control member and arm for longitudinally adjusting the member to rock the finger between operative and inoperative positions thereof.

6. A structure in accordance with claim 5 whereof the adjusting means for the control member comprises a cam lever directly operative against the bearing plate and pivotally carried by the control member.

7. In a device for clampedly holding a work-piece against a bed-plate, a clamping finger providing a forward work-engaging end and intermediately mounting a fulcrum pin in laterally extended fixed relation thereto, an arm fixedly related to the bed-plate in spaced opposed relation thereto and providing a longitudinal guideway beneath a top portion of the arm and fittedly receiving the ends of the fulcrum pin of the finger for a longitudinal adjustment of the finger with respect to the arm and beneath its top portion, a bearing plate frictionally engaging the upper face of the arm top and adjustable along the arm opposite an elongated opening provided through its top longitudinally thereof, a control member extending through said arm opening and operative in tension between the bearing plate and the rear end of the finger to clampedly engage the work-engaging end of the finger with a work-piece disposed between it and the bed-plate, and a spring means constantly and yieldingly operative between the rearward finger portion and the arm top for resisting an operative action of the control means and maintaining a frictional engagement of the bearing plate with the top face of the arm to provide for a set longitudinal adjustment of the plate and finger while the finger is inoperative with respect to a work-piece.
